Primary Examiner — T. Chase Nelson*Assistant Examiner* — John Windmuller(74) *Attorney, Agent, or Firm* — Montgomery Patent and Design; Robert C. Montgomery; Joseph T. Yaksich**CLAIM**

The ornamental design for hitch and customizable round hitch cover combination, as shown and described.

DESCRIPTION

FIG. 1 is a front perspective view of a first embodiment of a hitch and customizable round hitch cover combination showing my new design;

FIG. 2 is a top rear perspective view thereof;

FIG. 3 is a bottom rear perspective view thereof;

FIG. 4 is a front perspective view of a second embodiment of a hitch and customizable round hitch cover combination showing my new design;

FIG. 5 is a top rear perspective view thereof;

FIG. 6 is a bottom rear perspective view thereof;

FIG. 7 is an front perspective view of the customizable round hitch cover of the hitch and customizable round hitch cover combination shown separately for ease of disclosure only;

FIG. 8 is a front elevation view thereof;

FIG. 9 is a rear elevation view thereof;

FIG. 10 is a right side elevation view thereof;

FIG. 11 is a left side elevation view thereof;

FIG. 12 is a top plan view thereof; and,

FIG. 13 is a bottom plan view thereof.

The oblique views shown in FIGS. 1 through 6 are depicted slightly smaller for illustrative purposes only.
